UNITED STATES PATENT OFFICE.

WILLIAM H. HOPE, OF PROVIDENCE, RHODE ISLAND.

METHOD OF PREPARING PRINT-ROLLS FOR CLOTH-PRINTING.

1,255,881.

Specification of Letters Patent.

Patented Feb. 12, 1918.

Application filed July 22, 1916. Serial No. 110,704.

To all whom it may concern:

Be it known that I, WILLIAM H. HOPE, a citizen of the United States, residing at Providence, in the county of Providence and State of Rhode Island, have invented a new and useful Improvement in Methods of Preparing Print-Rolls for Cloth-Printing, of which the following is a specification.

This invention relates to certain new and useful improvements in the method of preparing print rolls for cloth printing, and more particularly to the preparation of the design from which the print roll is engraved before the same is etched.

It is known in the art of metal etching that upon the application of the acid, the acid will undercut the varnished or protected surface; therefore, in preparing a roll for the etching process the design is traced upon the roll by a cutter point in a suitable pantograph that removes the protecting surface of varnish and slightly cuts the design in the metal. In cases where the printing of cloth is in two or more abutting colors the operator in tracing the design from the pattern must leave sufficient space between the two colors forming the design to permit of such undercut by the acid as to bring the colors in contact, but not have them overlap one on the other in the printing. This requires great skill on the part of the operator of the pantograph.

The particular object of this invention is to provide a design or pattern of such nature that an ordinary operative can produce as good if not better work than is at present produced.

To this end applicant proceeds as follows:

40 In the drawings—

Figure 1 is a plan view of a portion of a design or pattern, and

Fig. 2 is a similar view of a design or pattern.

45 In proceeding in accordance with the present invention the designer outlines the design with a line 1 of such width as has been predetermined depending upon depth of the etching and the undercut.

50 Fig. 1 illustrates a design of a spot of one color to be printed upon cloth printed with any other color and illustrates a deep etching in which the printing roll will carry a heavy charge of color, as in printing goods having a pile surface.

The design, which may be of any configuration, it will be seen is outlined by a wide border and the operator in engraving the roll to print the design, a spot as shown, operates the stylus on the design by tracing 60 parallel lines 2 from the inside of the outline first at one angle (always left to right) and then at a higher angle. By using lines of two different angles the outline of the design is more perfectly preserved. The roll 65 for printing the background is engraved by the operators by bringing the stylus up to the outside of the outline and tracing the parallel lines 3. By the use of the design shown in Fig. 1 it will be seen that after 70 the two rolls have been etched the acid will have undercut the outline on each side so that upon applying color to the two rolls in a printing machine, the two colors, one forming the design and the other forming the 75 background, will just meet without either overlapping or leaving an irregular outline to the design.

Fig. 2 shows the design formed with a narrow outline 4 for engraving rolls from 80 which to print goods of lighter weave or texture, as the rolls are not required to carry as heavy a charge of color. It is evident to one versed in the art that by forming the outline of the design of such predetermined 85 width depending upon the depth of etching of the roll much more perfect print goods will be produced.

Having thus described my invention, what I claim as new and desire to secure by Letters Patent is—

1. The method of preparing print rolls for cloth printing, consisting in surrounding the design with a border line of predetermined width and conforming to the configuration of the design, such width to be equal to the amount of the undercutting of the acid, tracing a stylus along parallel lines across the design exclusive of its border line, operating a cutter on a roll according 95 to the movements of the stylus and etching 100 the roll.

2. The method of preparing print rolls for cloth printing, consisting in surrounding the design with a conformable border 105 line of a predetermined width, tracing a stylus along two angularly related sets of parallel lines inwardly from the inner edge and outwardly from the outer edge of the border line, operating a cutter on one roll 110

in accordance with the movements of the stylus within the border line, operating the cutter on a second roll according to the movements of the stylus outside the border line, and etching the cut rolls.

5 In testimony whereof I have signed my

name to this specification in the presence of two subscribing witnesses.

WILLIAM H. HOPE.

Witnesses:

ADA E. HAGERTY,

J. A. MILLER.
